BY

Ira L. Nickerson
ATTORNEY.

UNITED STATES PATENT OFFICE.

EDWARD W. STEVENS, OF DETROIT, MICHIGAN, ASSIGNOR TO CHICAGO PNEUMATIC TOOL COMPANY, OF NEW YORK, N. Y., A CORPORATION OF NEW JERSEY.

PNEUMATIC HAMMER.

Application filed July 30, 1926. Serial No. 125,835.

This invention relates to fluid pressure percussive tools. While it concerns tools of the described type in which the motive fluid is at least partly controlled by an automatically thrown valve and relates particularly to the valve and piston action of such tool generally, it has special application to that type of tool which utilizes a hammer piston provided with an interior chamber into which extends a motive fluid inlet plug.

5

One object of the invention is to improve the operating characteristics of fluid pressure tools of the type described. Another object is to simplify the structure and to lower the 15 cost of production. Other objects will be apparent from the detailed description which follows.

In order to illustrate the invention one concrete embodiment thereof is shown in the accompanying drawings,—which;

20

Fig. 1 is a longitudinal sectional view through a fluid pressure percussive tool; and

Fig. 2 is a view similar to Fig. 1 showing the parts in a different position.

25 The invention as illustrated is embodied in a pneumatic percussive tool having a cylinder 3 providing a piston chamber 4 in which reciprocates a hammer piston 5 imparting its blow to a working tool 6, such as a drill 30 steel, supported in a front head or chuck 7 either directly or through an intermediate member such as anvil block 8 which may be supported in a bearing member 9 interposed between cylinder 3 and front head 7. Piston 5 has an interior chamber or bore 10 opening into the rear end of the piston chamber through a slightly reduced opening or portion 10^a. The rear end of the piston chamber, which may be enlarged adjacent its 35 end by an annular groove 4^a, is sealed by a closure member having a head or cap portion 11 which partly telescopes within the piston chamber and has an integral plug extension or stem 11^a projecting axially within the piston chamber and cooperating with the bore 10^a of the piston. Extension 11^a is hollow or formed with a central bore 11^b to serve as a conduit for admitting motive fluid continuously to the interior of the piston 5. Extension 11^a also has its exterior reduced as indicated at 11^c to permit motive fluid from bore 10 of the piston to pass to the rear end of the piston chamber when the piston is in a rearward position as indicated in Fig. 2.

40

45

50

The head of the closure member may be undercut annularly as indicated at 11^c to form a cushion chamber or pocket for the rear end of the piston.

55 The admission of motive fluid to the front end of the piston chamber to be operative against the front end of the piston for the rearward stroke of the latter is controlled by an annular recess or groove 12 in the piston which registers with cross ports 13 and 14 in the cylinder walls, which ports connect respectively with live air passage 13^a and passage 14^a which opens into the extreme front end of the piston chamber through port 14^b. The piston also controls main exhaust ports 15 and 16 for the rear and front ends of the 70 piston chamber respectively.

60 A valve 17 arranged to be controlled by the piston has much to do with the proper functioning of the hammer. The valve is thrown to the rearward position indicated in Fig. 1 65 upon the admission of motive fluid to passage 14^a which motive fluid becomes directly effective against the front end of the valve. The valve is thrown to the forward position shown in Fig. 2 on admission of the motive fluid to the opposite end of the piston chamber by reason of a passage 18 extending from enlarged chamber 4^a to the rear end of the valve. A port 19 controlled jointly by piston 5 and valve 17 provides for the prolongation 80 of the admission of motive fluid to the front end of the piston chamber, while an annular groove 17^a in the valve arranged to cooperate 85 on the one end with a vent 20 and on the other with a piston controlled passage 21 opening 90 into the piston chamber in spaced relation to the rear end thereof provides an auxiliary exhaust for the rear end of the piston chamber.

95 The cycle of operation is as follows: Upon opening the manually controlled throttle valve 22 in back head 23 motive fluid is admitted to live air passage 24 having branches connecting with conduit 11^b and passage 13^a. If the parts are in the position shown in Fig. 1, the motive fluid from passage 13^a passes 100 around the recess 12 in piston 5 to port 14 extending in both directions to enter the front end of the piston chamber through port 14^b to start the piston on its rearward stroke and acting against valve 17 to move 105 it to the position shown in Fig. 1, if it is not already in that position. As the piston moves rearwardly it closes port 14 but the motive

fluid continues to pass to the front of the piston chamber since port 19 is still open, thus prolonging the admission of motive fluid until ports 13 and 19 are closed by the piston whereupon the rearward movement of piston 5 continues by expansion of the motive fluid. The opposite end of the piston chamber is open to exhaust through main exhaust port 15 and after the latter is closed by the piston, the trapped air continues to escape through the auxiliary vent formed by passage 21, groove 17^a in valve 17, and vent 20. Soon after passage 21 is closed by piston 5, the reduced internal bore 10^a of the piston registers with the reduced portion 11^c of extension 11^a whereupon motive fluid continuously admitted to the interior of the piston passes to the rear end of the piston chamber to become effective against the rear end of the piston to assist the constant pressure area within the piston to stop and to reverse the movement of the latter. Some of the motive fluid admitted to the rear end of the piston chamber is effective through passage 18 against the valve to throw it to the position shown in Fig. 2, the front end of the piston chamber being at this time open to exhaust through port 16. When the valve shifts it closes prolongation port 19 and breaks the connection between passage 21 and vent 20. The movement of the piston is now reversed, and it moves forward to strike its blow under the impulse of live motive fluid acting upon its interior pressure area and upon its rear end. Admission of motive fluid to the rear end of the piston chamber is shortly closed by the registering of the reduced bore 10^a with the unreduced portion of extension 11^a, whereupon the pressure of the expanding motive fluid previously admitted is now effective against the rear end of the piston. As the piston strikes its blow main exhaust port 15 is uncovered relieving the pressure in the rear end of the piston chamber, while at the same time ports 13 and 14 are again connected by the piston groove 12 to admit air to the front end of the piston chamber and to throw the valve to the position shown in Fig. 1, thus completing the cycle.

From the above it will be apparent that the present invention provides a fluid pressure hammer having an internal continuous pressure area and intermittent end areas controlled by the piston with a valve arranged to be thrown on admission of motive fluid to the said intermittent pressure areas of the piston, that means are provided jointly under control of the piston and of the valve for prolonging the admission of motive fluid to one intermittent area of the piston and for providing an auxiliary exhaust for the opposite intermittent area, and that the structure of hammers of this type is improved and the cost of manufacture and assembly lowered

by forming the plug conduit to the interior of the piston as an integral extension of the end closure for the piston chamber.

While a preferred form of the invention has been herein shown and described it is to be understood that the invention is not limited to the specific details thereof but covers all changes, modifications, and adaptations within the scope of the appended claims.

I claim as my invention:

1. A fluid pressure tool comprising a cylinder providing a piston chamber, a piston reciprocable in said chamber and having an internal bore, the end wall of said bore forming a pressure area for driving the piston forwardly, a fixed member extending axially into said piston chamber and into said bore to admit motive fluid continuously to said area, piston controlled means for intermittently feeding and venting motive fluid to the ends of the piston, an automatic valve controlled by said piston for prolonging the feeding of motive fluid to one end area of the piston and for providing an auxiliary exhaust for the other end area, and means utilizing motive fluid from the internal bore of said piston for moving the valve in one direction.

2. A fluid pressure tool comprising a cylinder providing a piston chamber, a piston reciprocable in said chamber and having an internal bore, the end wall of said bore forming a pressure area for driving the piston forwardly, a fixed member extending axially into said piston chamber and into said bore to admit motive fluid continuously to said area, piston controlled means for intermittently feeding and venting motive fluid to the ends of the piston, a valve controlled by said piston, means controlled by said valve for prolonging the feeding of motive fluid to the return end area of the piston while providing an auxiliary exhaust for the opposed end area of the piston in one position and for closing both said means when in another position, and means utilizing motive fluid from the internal bore of said piston for moving said valve in one direction and motive fluid from a separate supply passage controlled by said piston for the reverse movement of said valve.

3. A fluid pressure tool comprising a cylinder providing a piston chamber, a piston reciprocable in said chamber and having an internal bore, the end wall of said bore forming a pressure area for driving the piston forwardly, a fixed member extending axially into said piston chamber and into said bore to admit motive fluid continuously to said area, cooperating means on said member and said piston permitting motive fluid to pass to the adjacent end of the piston chamber to act against the end area of the piston in one position of the latter, a valve controlled by said piston, said cylinder providing an ex-

- haust port for said end of the piston chamber under control of said piston, means providing an auxiliary exhaust for said end of the piston chamber controlled both by said 5 valve and said piston and effective immediately prior to the admission of motive fluid to said end area, and means whereby said valve is shifted by the motive fluid admitted to said last named area.
- 10 4. A fluid pressure tool comprising a cylinder providing a piston chamber, a piston reciprocable in said chamber and having an internal bore, the end wall of said bore forming a pressure area for driving the piston 70 forwardly, a fixed member extending axially into said piston chamber and into said bore to admit motive fluid continuously to said area, cooperating means on said member and said piston permitting motive fluid to 75 pass to the adjacent end of the piston chamber to be effective against the end area of the piston in one position of the latter, a valve controlled by said piston, an auxiliary exhaust for said end of the piston chamber 80 controlled both by said valve and said piston and effective immediately prior to the admission of motive fluid to said end area, and means whereby said valve is shifted by the motive fluid admitted to said last named 85 area, piston controlled means for admitting motive fluid to the front end of the piston chamber to be effective against the front end of the piston for the return stroke of the latter, and means controlled jointly by said 90 piston and by said valve for effecting a limited prolongation of the admission of motive fluid to said front end.
- 35 5. A fluid pressure tool comprising a cylinder providing a piston chamber, a piston reciprocable in said chamber and having an internal bore, the end wall of said bore forming a pressure area for driving the piston forwardly, a fixed member extending axially into said piston chamber and into said bore to admit motive fluid continuously to said area, said member having a reduced portion to permit motive fluid to pass from said bore to the adjacent end of the chamber to be effective against the rear end of the piston, piston 95 controlled means for admitting motive fluid to the front end of the chamber to be effective against the front end of the piston for the return stroke of the latter, a valve, said valve being shifted in opposite directions on admission of motive fluid to the ends of the piston chamber, and means controlled by said valve for venting one end of the piston chamber prior to the admission of motive fluid thereto and for prolonging the admission of motive fluid to the other end, said means being operative in one position of the valve and 100 inoperative in another position of the valve.
- 40 6. A fluid pressure tool comprising a cylinder providing a piston chamber, a piston reciprocable in said chamber and having an internal bore, the end wall of said bore forming a pressure area for driving the piston forwardly, a fixed member extending axially into said piston chamber and into said bore to admit motive fluid continuously to said area, said member having a reduced portion to permit motive fluid to pass from said bore to the adjacent end of the chamber to be effective 105 against the rear end of the piston, piston controlled means for admitting motive fluid to the front end of the chamber to be effective against the front end of the piston for the return stroke of the latter, a valve, said valve being shifted in opposite directions on admission of motive fluid to the ends of the piston chamber, and means controlled jointly by said valve and by said piston for venting one end of the piston chamber prior to the admission of motive fluid thereto and for prolonging the admission of motive fluid to the other end.
- 45 7. A fluid pressure tool comprising a cylinder providing a piston chamber, a piston reciprocable in said chamber and having an internal bore, the end wall of said bore forming a pressure area for driving the piston forwardly, a fixed member extending axially into said piston chamber and into said bore to admit motive fluid continuously to said area, said member having a reduced portion to permit motive fluid to pass from said bore to the adjacent end of the chamber to be effective against the rear end of the piston, piston 110 controlled means for admitting motive fluid to the front end of the chamber to be effective against the front end of the piston for the return stroke of the latter, a valve, said valve being shifted in opposite directions on admission of motive fluid to the ends of the piston chamber, and means controlled by said valve for venting one end of the piston chamber prior to the admission of motive fluid thereto and for prolonging the admission of motive fluid to the other end, said means being operative in one position of the valve and 115 inoperative in another position of the valve.
- 50 8. A fluid pressure tool comprising a cylinder providing a piston chamber, a piston reciprocable in said chamber and having an internal bore, the end wall of said bore forming a pressure area for driving the piston forwardly, a fixed member extending axially into said piston chamber and into said bore to admit motive fluid continuously to said area, said member having a reduced portion to permit motive fluid to pass from said bore to the adjacent end of the chamber to be effective 120 against the rear end of the piston, piston controlled means for admitting motive fluid to the front end of the chamber to be effective against the front end of the piston for the return stroke of the latter, a valve, said valve being shifted in opposite directions on admission of motive fluid to the ends of the piston chamber, and means controlled jointly by said valve and by said piston for venting one end of the piston chamber prior to the admission of motive fluid thereto and for prolonging the admission of motive fluid to the other end.
- 55 9. A fluid pressure tool comprising a cylinder providing a piston chamber, a piston reciprocable in said chamber and having an internal bore, the end wall of said bore forming a pressure area for driving the piston forwardly, a fixed member extending axially into said piston chamber and into said bore to admit motive fluid continuously to said area, said member having a reduced portion to permit motive fluid to pass from said bore to the adjacent end of the chamber to be effective 125 against the rear end of the piston, piston controlled means for admitting motive fluid to the front end of the chamber to be effective against the front end of the piston for the return stroke of the latter, a valve, said valve being shifted in opposite directions on admission of motive fluid to the ends of the piston chamber, and means controlled jointly by said valve and by said piston for venting one end of the piston chamber prior to the admission of motive fluid thereto and for prolonging the admission of motive fluid to the other end.

9. A fluid pressure tool comprising a cylinder providing a piston chamber, a piston reciprocable in said chamber and having an internal bore, the end wall of said bore forming a pressure area for driving the piston forwardly, a fixed member extending axially into said piston chamber and into said bore to admit motive fluid continuously to said area, said member having a reduced portion to permit motive fluid to pass from said bore to the adjacent end of the chamber to be effective against the rear end of the piston, piston controlled means for admitting motive fluid to the front end of the chamber to be effective against the front end of the piston for the re-

turn stroke of the latter, a valve, said valve being shifted in opposite directions on admission of motive fluid to the ends of the piston chamber, and means controlled jointly by said valve and by said piston for venting one end of the piston chamber prior to the admission of motive fluid thereto and for prolonging the admission of motive fluid to the other end, said means being operative in one position of the valve and inoperative in another position of the valve.

Signed by me at Detroit, Michigan this 27 day of July 1926.

EDWARD W. STEVENS.
